his Atty's.

UNITED STATES PATENT OFFICE.

HOWARD H. UTLEY, OF FLORENCE, COLORADO, ASSIGNOR TO RIVER SMELTING & REFINING COMPANY, OF ST. LOUIS, MISSOURI, A CORPORATION OF MAINE.

SYSTEM FOR COOLING FLUE GASES.

Application filed January 6, 1921. Serial No. 435,413.

To all whom it may concern:

Be it known that I, HOWARD H. UTLEY, a citizen of the United States, and a resident of the city of Florence, in the county of Fremont and State of Colorado, have invented a new and useful Improvement in Systems for Cooling Flue Gases, of which the following is a specification.

This invention relates to means for reducing the temperature of the flue gases and eliminating the fume therefrom. One of the principal objects of the present invention is to equip the cooling system with separate and independent pipe or unit sections whose number may be increased or decreased according to the amount of heat it is desired to remove from the flue gases. Another object is to permit the removal or changing of any one of the cooling units without disturbing the others and without interfering with the operation of the other units of the system. Another object is to provide each unit of the cooling system with a separate positive water control or regulation. Another object is to facilitate easy cleaning of each cooling unit and to reduce the cost and to simplify the construction of the cooling system by making the units of standard stock parts capable of easy repair and replacement. Another object is to provide flexible connections between each individual unit and the water supply and thereby allow for expansion and contraction of the units. Another object of the flexible connection is to permit the units to be lifted and dropped whereby the jar resulting from the dropping of the units will shake off most of the light dust which deposits on the units.

The invention consists principally in a cooling system comprising a plurality of separate cooling units disposed crosswise of the furnace flue and having separate connections with the supply of cooling medium whereby each individual cooling unit is adapted to be removed and replaced without disturbing the connection between the remaining cooling units and the supply of water or other cooling medium therefor; it also consists in making the connections between said units and the water supply flexible, whereby they are permitted to expand and contract individually and are adapted to be bodily lifted and dropped to jar off the accumulated dust without inter-

rupting the flow of water to or from the cooling units. The invention further consists in the combinations and arrangements of parts hereinafter described and claimed.

In the accompanying drawing, which forms part of this specification, and wherein like symbols refer to like parts wherever they occur;

Fig. 1 is a diagrammatic view in longitudinal vertical section of a reverberatory furnace; a cooling system embodying my invention being shown in connection therewith;

Fig. 2 is an enlarged fragmentary side elevation of the furnace in the region of the cooling system, showing the separate flexible connections between a plurality of cooling units and a water header; and

Fig. 3 is a vertical section taken crosswise of the cooling conduit on the line 3—3 in Fig. 2.

The accompanying drawing illustrates diagrammatically an ordinary type of reverberatory furnace 4 which comprises a furnace chamber 5 having a floor or hearth 6 on which the ore charge is exposed to the flame. The ore charge comprises a mixture of ore and reducing and matte-forming material and is inserted into the furnace chamber near the front end thereof through ore charging hoppers 7. The heat necessary to melt the charge is produced by means of powdered coal which is blown into the firing end of the furnace through pipes 8. The matte is removed from the furnace chamber through a tap hole 9 located close to the hearth of the furnace. The slag is removed from the furnace chamber through a tap hole 10 located above the matte tap 9. The hot gases and metallic fume escape from the furnace chamber through an opening 11 in the rear wall thereof and pass through a long flue or cooling passageway 12 which discharges into a plurality of bags contained in an ordinary bag house (not shown), which bags allow the escape of the products of combustion, but retain the solids.

The temperature of the fume laden gases in the cooling passageway 12 is reduced by means of a water cooling system comprising a plurality of cooling units 13 which extend crosswise of the passageway. The units are spaced from each other in both vertical and horizontal directions, and their number depends upon the amount of heat desired to be

removed. The units extend through aligned apertures 14 in the opposite side walls of the cooling passageway with their ends resting on the bottoms of said apertures. Each 5 unit comprises an outer cylindrical casing or pipe section 15, which is closed at both ends, and an inner cylindrical casing or pipe section 16. The inner pipe sections 16 extend centrally through the outer pipe sections 15 and open into the interior of said outer pipe sections near the rear end thereof. The front end of the outer pipe section 15 of each unit has a rigid connection 17 with the upper end of a vertically disposed outlet or overflow pipe 18. The lower ends of the outlet pipes 18 terminate at a point above a main overflow trough (not shown) so as to empty into said trough.

15 The inlet pipes 16 of the units have flexible 20 connections 19, preferably in the form of short sections of hose, with water headers or drums 20, which communicate with a suitable source of water supply. A separate header is preferably provided for every four 25 or five units.

With the arrangement described, the water control of each cooling unit is independent, and each individual unit of the cooling system can be removed or changed 30 without disturbing the remaining units. The flexible connections 19 between the inlet pipe sections 16 and the headers 20 permit the expansion and contraction of the units without interrupting or disturbing the flow of 35 water to and from said units. These flexible connections also permit movement of the pipe sections bodily without interrupting the flow of water therethrough whereby the ends of the pipes may be raised and dropped 40 for cleaning purposes, the jar resulting from the dropping of the pipe sections tending to shake off most of the matter which is deposited thereon. The units may also be cleaned in the usual manner, as by means 45 of a curved scraper. The apertures in which the ends of the units rest are of a greater vertical dimension than the diameter of the units, thus leaving a space of sufficient size to permit entry of the curved scraper and 50 to permit the pipe section to be raised and lowered. The spaces between the tops of the pipe and the tops of the apertures are closed by means of plates 21. These plates have their lower ends shaped to fit the curved 55 surface of the pipe section, and are provided with eyes or ring portions 22 whereby the plates are adapted to be removed by means of a hooked rod.

60 The hereinbefore described construction permits of considerable modification without departing from the invention; therefore, I do not wish to be limited to the details of construction shown and described. For instance, the rigid connection 17, between the 65 upper ends of the vertical overflow pipes 18

and the inner pipe section 16, may be made in the form of hose connections, and the lower ends of said pipes rigidly connected to a main overflow pipe. This arrangement would permit the units to be lifted without 70 lifting the overflow pipes. Likewise, the invention is applicable not only to reverberatory and other metallurgical furnaces but also to boiler and other furnaces generally. Likewise, it is obvious that some other cooling medium may be used in place of water, such as oil or other liquid or even gases like air.

What I claim is:

1. In a furnace comprising a heating 80 chamber and a flue leading therefrom, a cooling system for said flue comprising a plurality of separate cooling units, a supply 85 of cooling medium and an overflow for said units, and means whereby said units are permitted to expand and contract and are capable of being moved bodily without interrupting the flow of cooling medium to and from the same, each unit consisting of a cylindrical shell closed at its ends and a pipe 90 connected to said supply and extending through one end of said shell and terminating therein close to the other end thereof.

2. In a furnace comprising a heating chamber, and a flue leading therefrom, a cooling system for said flue comprising a plurality of separate units, separate liquid supply and overflow pipes for each of said units, and means whereby said units are adapted for bodily movement within certain 100 limits without interrupting the flow of liquid to and from the same, each unit consisting of a cylindrical shell closed at its ends and a pipe connected to said supply and extending through one end of said shell 105 and terminating therein close to the other end thereof.

3. In a furnace comprising a heating chamber and a flue leading therefrom, a cooling system for said flue comprising a 110 plurality of separate units disposed horizontally crosswise of said flue with their ends resting in apertures formed in the opposite side walls thereof, a supply of cooling liquid for said units and an outlet therefor, and means whereby said units are adapted 115 to be removed and inserted independently of each other and without disturbing the flow of liquid to and from the remaining units.

4. In a furnace comprising a heating chamber and a flue leading therefrom, a water cooling system for said flue comprising a plurality of separate units disposed crosswise in said flue with their ends resting in apertures formed in the opposite walls thereof, said units being spaced apart in both horizontal and vertical directions, water headers for said units and overflow pipes therefor, and a separate flexible con- 120

nection between each of said units and said water headers, whereby the disconnecting of the flexible connection between a unit and the water header therefor permits said unit to be removed and replaced without interfering with the operation of the furnace or the operation of the remaining unit of said cooling system.

5. In a metallurgical furnace comprising a heating chamber and a flue leading therefrom, a water cooling system for said flue comprising a plurality of separate casings disposed crosswise of said flue and supported at their opposite ends in aligned apertures formed in the opposite side walls thereof, a water supply and a water overflow for each of said casings, the apertures in which the ends of said casings are supported being larger than the diameter of said casings whereby an opening is formed to permit entry of a device for scraping said casings, and separate flexible connections between each of said casings and the said water supply and overflow, whereby light ore dust 20 deposited on said casings can be removed by lifting and dropping an end of a casing without interrupting the flow of water to and from the same.

6. In a metallurgical furnace comprising a heating chamber and a flue leading therefrom, a water cooling system for said flue comprising a plurality of horizontally disposed separate cylindrical casings arranged crosswise of said flue with their ends resting in apertures formed in the opposite walls thereof, a water supply and a water overflow for said casings said apertures being of a greater height than the diameter of said casings, whereby an opening is left between the tops of said apertures and said casings, separate flexible connections between each of said casings and the said water supply and overflow, whereby light ore dust is adapted to be removed from said

casing by the action of raising and dropping an end of a casing without interrupting the flow of water to and from the same, and removable cover plates for covering the openings between the tops of said casings and the tops of the aperture therefor.

7. In a metallurgical furnace comprising a heating chamber and a flue leading therefrom, a water cooling system for said flue comprising a plurality of separate units disposed therein, each of said units comprising an outer casing and an inner casing extending through one end of said outer casing and communicating with the interior thereof, a water supply and a water outlet for said units, and a separate flexible connection between the outer casing of each unit and the water outlet and between the inner casing and the water outlet, whereby said units are permitted to expand and contract and are capable of being moved bodily without interrupting communication between said units and the water supply and water outlet.

8. In a metallurgical furnace comprising a heating chamber and a flue leading therefrom, a water cooling system for said flue comprising a plurality of separate units disposed crosswise in said flue with their ends supported in apertures in the walls thereof, each of said units comprising spaced inner and outer casings communicating with each other at one end of the unit, a water supply and a water outlet for said units and a separate flexible connection between the outer casing of each unit and said water supply, whereby said units are permitted to expand and contract and are capable of being moved bodily in said apertures without interrupting the flow of water to and from the same.

Signed at St. Louis, Missouri, this 31st day of December, 1920.

HOWARD H. UTLEY.
